[57] CLAIM

The ornamental design for a lug strap, as shown and described.

DESCRIPTION

FIG. 1 is a perspective view of the lug strap showing my new design;

FIG. 2 is an end elevational view taken from the left of FIG. 5;

FIG. 3 is an end elevational view taken from the right of FIG. 5;

FIG. 4 is a top plan view thereof;

FIG. 5 is a front elevational view thereof;

FIG. 6 is a sectional view taken in the direction of the arrows on line VI-VI of FIG. 1.

The rear elevational view of the strap is a mirror image of FIG. 5, while the bottom plan view is the same as FIG. 4.

UNITED STATES PATENT AND TRADEMARK OFFICE
